UNITED STATES PATENT OFFICE.

ALBERT VICTOR HORNER, OF TORONTO, ONTARIO, CANADA.

WINDOW CONSTRUCTION.

1,367,970.

Specification of Letters Patent.

Patented Feb. 8, 1921.

Application filed February 28, 1920. Serial No. 361,938.

To all whom it may concern:

Be it known that I, ALBERT VICTOR HORNER, a subject of the King of Great Britain, residing at 504 Caledonia avenue, in the 5 city of Toronto, in the county of York, in the Province of Ontario, Canada, have invented certain new and useful Improvements in Window Constructions, of which the following is the specification.

10 My invention relates to improvements in window constructions and the object of the invention is to devise means whereby either sash may be independently removed from the frame for the purpose of cleaning the 15 window and to perform this operation easily and almost instantaneously with a minimum amount of labor and it consists essentially of the arrangement and construction of parts as hereinafter more particularly explained.

Figure 1 is a perspective view of the window frame showing the sashes in the closed position and partly broken away and in section.

25 Fig. 2 is a sectional plan view taken through the upper sash.

Fig. 3 is an enlarged sectional detail of the latching device employed in connection with my window sash showing it in the 30 locked position.

Fig. 4 is a similar view to Fig. 3 showing the sash removed and the lock in the unlocked position.

Fig. 5 is a sectional detail through a portion of the window frame, sash guide, and sash.

Fig. 6 is an edge view of a portion of the window sash showing the locking lever in section in engagement with the keeper.

40 In the drawings like characters of reference indicate corresponding parts in the various figures.

1 indicates the window frame provided with the usual vertical casing portions 2 and

45 3, sill 4 and lintel 5. The frame 1 is provided with the usual stop strip 6, parting strip 7 and outer strip 8 forming the usual guide ways 9 and 10 for the upper and lower sash. 11 and 12 are pulleys for the lower

50 sash secured within the casing portions 2 and 3 in the usual manner. 13 and 14 are pulleys also mounted in the casing portions 2 and 3. 15 are the cords passing over the pulleys 11 and 12 and to which the lower

55 sash is usually connected and 16 and 17 are cords passing over the pulleys 13 and 14 to

which the upper sash is usually connected. The opposite ends of the cords 15, 16 and 17 are provided with the usual counter weights (not shown). 18 is a guide strip slideable 60 within the guide way 10 of the window frame. 19 is a similar guide strip slideable within the opposing guide way 10 located at the outer side of the casing portion 3. The cords 16, 17 are connected to the lower ends 65 of these guide strips as indicated at 20, Fig. 2.

Each guide strip 18 and 19 is provided with a vertical rabbet 21 at its inner edge and a rabbet 22 in proximity to its outer edge forming shouldered portions 23 and 24. 25, 25 are similar guide strips slideable within the opposing guide ways 9 to the outer ends of which are secured the cords 15. The guide strips 25 are provided with vertical rabbets 26 and 27 forming shoulders 28 and 29. 30 is the upper sash the vertical portions 31 and 32 of which are correspondingly rabbeted and shouldered so as to fit into the grooves 21 and 22 and against the shoulders 23 and 24 as the sash is placed between the guide strips 18 and 19.

In order to insure of the sash being placed in the correct position as it is placed between the guide strips 18 and 19 I have provided each guide strip with a tongue 33 extending across the groove 22 the opposing portion of the sash 30 being provided with a cross recess 34 into which the tongue of the guide strip fits. The width of the removable portion of the upper sash must be the same or slightly less than the distance between the parting strips 7 so as to enable the upper sash to be withdrawn inwardly when removed.

95 The guide strips 25 must be of less width at their inner or widest portion than the projecting portion of the parting strips 7 for the same purpose so that the upper sash may pass as it is withdrawn inwardly.

100 35 is the lower sash which is also formed to fit into the grooved portions 26 and 27 of the guide strips 25 and is provided with a cross recess 36 into which fits the cross tongue 37 extending from each guide strip. 105 By means of the tongues 37 and 33 fitting into the recesses 36 and 34 the sashes and guides are connected together so as to move up and downward in unison when the operator of the window pulls up or down upon 110 the sash to be raised or lowered.

It is also necessary to provide means for

automatically locking the guide strips in place when the window sash is removed so that they will be held against being carried upward by the sash weights attached thereto. I will now describe this locking means which is particularly illustrated in Figs. 3, 4 and 6.

10 The edge of each sash is provided intermediately of its height with a recess 38 which is cut into that portion of the sash opposing the shoulder 24 of the guide strip thereby forming an exit orifice 39 for the locking lever which I will hereinafter describe.

15 40 is a plate which is secured to the edge of the sash below the recess 38 and is provided with an inrolled upper edge 41 which enters into the recess the upper contour of which is in the form of a notch 42 the outer 20 side of the notch being extended upward at 43. 44 is a slot cut in each guide piece in which is pivotally mounted a locking lever 45 which is in the form of a bell crank the horizontal arm 46 being hooked in shape so 25 as to extend around and fit the inner rolled portion 41 of the plate 40 when in the locking position. The other arm 47 of the locking lever extends upward normally against the face of the guide way in which the guide 30 strip moves. 48 is a recess formed in the base of each guide way the upper edge of the recess being provided with a V-shaped notch 49. 50 is a tension spring connecting the horizontal arm 46 of the locking lever 35 to the bottom of the slot 44.

Having described the principal parts involved in my invention I will briefly describe the operation of the same.

40 It may be first stated that a suitable portion of the frame 1 is provided with an indicating mark such as shown at 51 and the sash with an indicating mark such as shown at 52. The outer sash is also provided with corresponding indicating marks. When the 45 sash 35 is raised so that the indicating marks 51 and 52 are opposite, the vertical arm of the lever 45 is brought opposite the recess 48. The window sash is then gripped by the operator and drawn directly inward 50 into the room. By this operation the upwardly extending portion 43 formed at the side of the notch 42 of the plate 40 engages the horizontal arm 46 of the lever 45 tilting this arm of the lever upward against the 55 tension of the spring 50 thereby throwing the upper end of the arm 47 of the lever 45 into the recess 48. As the sash is withdrawn, being held in the hands of the operator, the weight of such sash is relieved and the sash 60 weights serve to draw the guide strips 25 upward so that the outer end of the lever arm 47 engages with the notch 49 and is thereby thrown to its final position enabling the sash to be drawn completely outward

and the horizontal arm 46 of the locking 65 lever to pass through the exit orifice 39. The guides 25 are thus supported in position ready to again receive the window sash after the window has been cleaned.

In inserting the sash all that it is necessary to do is to place the sash between the guide ways so that the cross rib 37 enters the cross recess 36, the horizontal arm 46 of the locking lever being in its final upper position allowing of the upward extension 75 43 of the plate 40 to pass beneath such arm into position. The window sash is then drawn down, being connected to the guides 25 by the tongues 37, fitting the recesses 36, carrying the guide strips down and with 80 them the locking lever 45. By this operation the upper ends of the arms 47 of the levers are withdrawn from the notches 50 acting to carry the levers again into the locking position in engagement with the 85 notches 42.

It will, of course, be understood that the upper sash is similarly operated so as to remove it and replace it in position.

From this description it will be seen that 90 I have devised a very simple device whereby the sash may be easily withdrawn from the window for the purpose of cleaning which operation may be done very quickly, almost instantaneously and replaced in position by 95 a simple operation which is just as instantaneous.

What I claim as my invention is:

1. In a window construction, the combination with a window frame having the usual 100 vertical guide ways, of guide strips slidably supported within the guide ways and to which the usual sash cords and sash weights are adapted to be connected, an independent window sash fitting between the guide strips 105 and provided with a cross recess having an open outer end, shouldering means carried by the guide strips against which the window sash bears when inserted therebetween, a horizontal tongue formed on the inner 110 face of each guide strip and adapted to enter the open outer end of the recess to fit the recess as the sash is placed in position between the guide strips, and means for automatically locking the guide strips to the 115 window frame operated by the withdrawal of the sash.

2. In a window construction, the combination with the window frame having guide ways, of a guide strip slidable within each 120 guide way and to which the sash cords and sash weights are adapted to be connected, of a window sash fitting between the guide strips and engageable therewith and having a recess in each edge, a lever pivoted within 125 each guide strip and entering the recess of the sash, and means within the recess of the sash for forcing the opposite end of the

lever into locking engagement with the frame operated by the withdrawal of the sash from between the guide strips.

3. In a window construction, the combination with the window frame having the usual guide ways each provided with a recess in the base thereof, of guide strips slidably fitting within the guide ways and to which the usual sash cords and weights are adapted to be connected, a window sash fitting between the guide strips and engageable therewith and having a recess in each vertical edge, a plate secured to each verti-
- cal edge of the sash and having a notched outer end, a bell crank shaped lever mounted 15 within each guide strip the horizontal arm of which is resiliently mounted and provided with a hook engaging the notched plate of the sash and the vertical arm of which is normally in slidable engagement 20 with the bottom of the window frame slide way and adapted to enter the recess of the slide way when brought opposite thereto and as the window sash is withdrawn.

ALBERT VICTOR HORNER.
